UNITED STATES PATENT OFFICE.

SHERWOOD HINDS, OF CHICAGO, ILLINOIS, ASSIGNOR TO ST. LOUIS PUMP & EQUIPMENT COMPANY, OF ST. LOUIS, MISSOURI, A CORPORATION OF MISSOURI.

DISPENSING APPARATUS.

Application filed July 1, 1921. Serial No. 481,733.

To all whom it may concern:

Be it known that I, SHERWOOD HINDS, a citizen of the United States, and a resident of Chicago, county of Cook, State of Illinois, have invented an Improvement in Dispensing Apparatus, of which the following is a specification.

This invention relates to mechanical apparatus, and with regard to certain more specific features, to filling stations.

Among the several objects of the invention may be noted the provision of simple and compact liquid-dispensing apparatus; the provision of reliable and durable means for indicating and for recording the amounts of liquid dispensed; and the provision of apparatus inexpensive in construction, accurate in operation, easily assembled, and readily disassembled for inspection or repair. Other objects will be in part obvious and in part pointed out hereinafter.

The invention accordingly comprises the elements and combination of elements, features of construction, and arrangements of parts which will be exemplified in the structure hereinafter described, and the scope of the application of which will be indicated in the following claims.

In the accompanying drawings, in which is illustrated one of various possible embodiments of the invention,

Fig. 1 is a front elevation;

Fig. 2 is a left side elevation;

Fig. 3 is a rear elevation;

Fig. 4 is a right side elevation;

Fig. 5 is a perspective of the front and right sides, with side covers removed;

Fig. 6 is a horizontal section on the line 6-6 of Fig. 1, with the casing removed;

Fig. 7 is a vertical longitudinal section on the line 7-7 of Fig. 6;

Fig. 8 is a horizontal section on the line 8-8 of Fig. 1;

Fig. 9 is a horizontal section on the line 9-9 of Fig. 1;

Fig. 10 is a horizontal section on the line 10-10 of Fig. 1;

Fig. 11 is a vertical transverse section on the line 11-11 of Fig. 9;

Fig. 12 is a vertical longitudinal section on the line 12-12 of Fig. 11;

Fig. 13 is a horizontal section on the line 13-13 of Fig. 2;

Fig. 14 is a vertical longitudinal section on the line 14-14 of Fig. 13, showing the parts in neutral position;

Fig. 15 is a view similar to Fig. 14, showing the parts in inlet position, that is, in their position during the inlet event of the cycle of operations;

Fig. 16 is a view similar to Fig. 14, showing the parts in discharge position, that is, in their position during the discharge event of the cycle;

Fig. 17 is a vertical transverse section on the line 17-17 of Fig. 13, the switch box being broken away;

Fig. 18 is a vertical longitudinal section on the line 18-18 of Fig. 13;

Fig. 19 is a vertical longitudinal section on the line 19-19 of Fig. 13, showing the parts in neutral position;

Fig. 20 is a view similar to Fig. 19, showing the parts in inlet position;

Fig. 21 is a view similar to Fig. 19, showing the parts in discharge position;

Fig. 22 is a vertical longitudinal section on the line 22-22 of Fig. 13;

Fig. 23 is a vertical transverse section on the line 23-23 of Fig. 13, showing in solid lines the emptying valve closed, and in dotted lines the emptying valve open;

Fig. 24 is a vertical transverse section on the line 24-24 of Fig. 22, showing the parts in neutral position;

Fig. 25 is a view similar to Fig. 24, showing the lock shaft in locking position;

Fig. 26 is a vertical longitudinal section on the line 26-26 of Fig. 13, showing the parts in neutral position;

Fig. 27 is a view similar to Fig. 26, showing the parts in inlet position;

Fig. 28 is a view similar to Fig. 26, showing the parts in discharge position;

Fig. 29 is a plan with the dome swung open;

Fig. 30 is a horizontal section on the line 30-30 of Fig. 31;

Fig. 31 is a vertical longitudinal section on the line 31-31 of Fig. 30;

Fig. 32 is a vertical transverse section on the line 32-32 of Fig. 30;

Fig. 33 is a vertical transverse section on the line 33—33 of Fig. 29;

Fig. 34 is a vertical longitudinal section on the line 34—34 of Fig. 29, parts being 5 broken away;

Fig. 35 is a fragmentary vertical longitudinal section on the line 35—35 of Fig. 33;

Fig. 36 is a vertical transverse section on 10 the line 36—36 of Fig. 29;

Fig. 37 is a view similar to Fig. 36, showing the parts in locking position;

Fig. 38 is a rear elevation of the lock and associated elements, showing the parts in 15 neutral position;

Fig. 39 is a view similar to Fig. 38, showing the lock shaft in locking position, but with the handle away from the lock;

Fig. 40 is a view similar to Fig. 38, showing 20 the parts in locking position, with the lock closed; and

Fig. 41 is a horizontal section on the line 41—41 of Fig. 39.

Similar reference characters indicate 25 corresponding parts throughout the several views of the drawings.

Construction—In general.

30 Referring now more particularly to Figs. 1 to 5 of the accompanying drawings, there is illustrated an apparatus, in this instance a gasoline filling station of the so-called "visible" type, comprising what may be 35 termed a series of six sections or compartments or levels numbered 1 to 6 respectively. The first, second, fourth and sixth levels have floors, separating the level more or less completely (as the case may be) from the level below.

In the first level 1 are located the inlet and overflow pipes from and to a reservoir (not shown), the motor, the wiring junction box, and the separator or filter.

45 In the second level 2 is mounted the pump and the clutch for disconnecting the motor from the pump.

In the third level 3 are mounted the hand-operated drive for the pump, the operating 50 handles, the lock handle, the discharge pipe and hose, the lock, and mechanism associated with these several parts.

In the fourth level 4 is mounted a container, quantity indicators and float therein, 55 a surrounding protective screen, supply pipe, distributor head and overflow pipe, and the emptying valve.

In the fifth level 5 is a dome hinged to the apparatus at the fifth floor, the totalizer, 60 the totalizer gearing for driving the totalizer, and the float gearing connecting the float to the totalizer gearing.

In the sixth level 6 is a translucent globe 65 for illuminating and/or advertising purposes.

For convenience, the six levels will be considered separately.

First level—(Figs. 6, 7 and 8).

The base 10 is a casting having a hole 12 70 at each of its four corners so that the base can be attached to a floor or other surface, and having a rectangular recess 11 for making readily accessible the wiring connections.

The motor M has a shaft 14 which runs 75 from front to back of the machine and has on its front end a pulley 16 to receive a link type V belt 17. The belt runs over a clutch pulley 19 loosely mounted on the shaft 21 of the pump P in the second level.

The inlet pipe 23 extends horizontally into the left side of the machine near the rear, and goes into a separator or filter S.

The separator S comprises a chamber 25 through which the liquid passes upwardly, 80 thence horizontally into a chamber 26 in one side of which is located a filter screen 27.

The gasoline passes upwardly through the filter screen, thence upwardly into chamber 28, from which it enters the inlet pipe 23 85 extending up and into the inlet side of the pump P on the second level.

The separator parts are so constructed 90 that the water-discharge port 29 is reached through the restricted passage between chamber wall and filter screen, thus providing an increased velocity of fluid at this point and increased centrifugal force, to facilitate the separation of water and gasoline. The water and other impurities, thus 100 thrown outwardly, sink to the lower part of chamber 26, thence through the water-discharge port 29 to the water chamber 32, whence they may be withdrawn by opening the locked faucet 32^a and producing (if necessary) a flow of gasoline downward 105 from the inlet pipe above the pump, so that said gasoline displaces the water in the separator.

The overflow pipe 33 extends horizontally 110 into the left side of the machine, forwardly of the inlet pipe 23, and thence passes upwardly through the second, third and fourth levels.

At the right front of the machine is a 115 pipe 47 extending through the first, second and third levels for steadyng purposes and for housing the electric wires to the motor switch. If there is a lamp on the sixth level, additional wiring is provided in this pipe 120 for such lamp, and suitable conduit is provided in the fourth, fifth and sixth levels for such wiring.

Second level—(Figs. 9, 11 and 12).

125 The pump P, which is preferably of the rotary type, has the shaft 21 above mentioned, extending from front to rear of the machine, and carrying loosely mounted adjacent its forward end the clutch pulley 19 130

carrying the motor belt 17. The pump shaft carries also a sprocket 37. On this sprocket is a chain 41 passing upwardly over a sprocket 43 in the third level, the latter 5 sprocket being connected to the hand drive of the machine.

The gasoline inlet 23 to the pump is at the left of the machine, and the outlet from the pump is connected to the inlet pipe I, 10 which runs upwardly through the third level on the right side of the machine, and enters the container in the fourth level.

The overflow pipe 33 passes upwardly through the second level at the left side of 15 the machine and extends up to the third level to the by-pass valve BV (Figs. 13, 15 and 18) and thence through the container C in the fourth level.

At the left front is a small rod 45 that 20 is simply for steadyng purposes, extending through the second and third levels only.

At the right front is the pipe 47 above mentioned.

25 *Third level—(Figs. 10, 13 to 28, and 36 to 41).*

In the lower part of the third level (Fig. 10) there are simply the three pipes and the 30 rod above mentioned, namely, inlet pipe I at the right, overflow pipe 33 at the left, wiring pipe 47 at the right front, and steadyng rod 45 at the left front.

In the middle part of the third level (Figs. 10, 11 and 12) a bracket 49 (Fig. 10) 35 is mounted on the inlet and overflow pipes I, 33, and carries a shaft 51 extending from front to rear of the machine. This shaft carries at its rear end a handle HC, and at its forward end sprocket 43.

40 In the upper part of the third level (Figs. 13 to 28, 36 and 37) are the operating handles OH at either side (Figs. 2 and 4), the lock-handle LH at the rear (Fig. 3), the lock L (Fig. 3) at the rear, the discharge pipe and hose D (Figs. 1 and 5) at the front, and the mechanism associated with these several parts. These parts and 45 their functions will be considered separately.

50 The two operating handles OH (Figs. 2 and 4) are located at the left and right sides of the machine respectively, forward of the middle. The handles move together, and are connected to a horizontal transverse 55 operating shaft OS that is journaled in brackets 53 at either side of the machine.

The operating shaft OS (Figs. 13 and 17) has fixed on it five devices O1, O2, O3, O4, 60 O5.

65 Reading from left to right of the machine the first device O1 (Figs. 24-28) is practically a segmental disc extending upwardly from the operating shaft and having a slot or notch 55 into which extends a vertical transverse disc L1 on the horizontal

longitudinal lock shaft LS hereinafter described, located just above the operating shaft OS. When the lock shaft is in neutral position, that is, with the lock handle LH (Fig. 3) down, a slot or notch 57 in the lock 70 shaft disc L1 registers with the operating shaft disc O1, and the notch 55 on the latter disc also registers with the former disc; so that in this position of the discs, corresponding to neutral position (down) of the lock 75 handle LH and neutral position (up) of the operating handles OH, either shaft can be rotated. But when either shaft is out of such position, the other shaft cannot be rotated, as the movement of either shaft 80 from neutral takes its notch out of the plane of the disk on the other shaft and thus prevents rotation of the other disc and shaft. There is thus an interlock between the two shafts. And since the locking of 85 the machine is effected by locking the lock shaft, such lock therefore locks in neutral position the operating shaft and the five devices controlled thereby, as well as the lock shaft and the several devices that it controls. 90

Reading still from left to right, the second device O2 (Fig. 18) on the operating shaft operates a by-pass valve BV that connects the inlet pipe I to the overflow 33 when the valve is open. As the overflow pipe is larger than the inlet pipe, and offers a free path down to the reservoir, all of the gasoline that may be pumped into the inlet pipe when the by-pass valve is open passes down through the overflow pipe and none of it reaches the container. The by-pass valve is opened by the forward or discharge movement of the operating handles, and prevents the passage of any gasoline to the container during discharge, even though the 100 operator in some way keeps the pump running during discharge. This second device is shown in neutral position in Figs. 17, 105 18 and 26, and in discharge position in Fig. 28. 110

The third or middle device O3 (Figs. 17, 26, 27 and 28) on the operating shaft extends forwardly and is connected to a vertical link 59 slotted as at 61 to receive a horizontal bolt 63 that serves simply to 115 guide the link. During rearward or inlet movement of the operating handles the link rises from its neutral position shown in Fig. 26 and thus has no effect on the weight. Forward or discharge movement of the 120 operating handles depresses this link, the lower end of which engages a branch 65 of the forward arm 67 of the weight lever 69, so that the downward movement of the link, caused by the discharge movement of the 125 operating handles, raises the weight W to the discharge position shown in Fig. 28.

The fourth device O4 (Figs. 14-21) on the operating shaft is an arm extending upwardly and bifurcated to receive a for- 130

wardly extending link 71 whose forward end is mounted in the bifurcated rear end of rod 73 having a lost-motion engagement with a lever 74 engaging the discharge or dispensing valve DV. Rearward or inlet movement of the operating handles (Fig. 20) has no effect on the discharge valve. Forward or discharge or dispensing movement of the operating handles pushes the stem 75 rearward (Fig. 21), opening the discharge valve and thereby allowing gasoline to flow from the container C in the fourth level out through the discharge pipe and hose D.

16 The fifth device O5 (Figs. 14-21) on the operating shaft comprises an arm 76 extending downwardly to the rear and terminating in a knob 77 engaging an upwardly extending slotted arm 79 of a bell-crank lever 81 whose other arm 83 extends horizontally forward and is bifurcated both horizontally and vertically to extend on the upper left, upper right, lower left, and lower right sides of a horizontal disc 85 which is on a vertical 20 rod 87 that operates the motor switch MS. Rearward or inlet movement of the operating handles causes this fifth arm to move downwardly and forwardly (counterclockwise in Figs. 19, 20 and 21) from the neutral 25 position shown in Fig. 19 to the inlet position shown in Fig. 20, thereby moving the bell-crank clockwise (viewed from the left side as in Figs. 19 and 20), which means that the forward bifurcated end of the bell-30 crank arm 83 moves down, thereby moving the horizontal disc 85 and its vertical rod 87 down. This downward movement of the rod does two things: first, it closes the motor switch MS, and second, it engages another 35 part 89 of the weight lever 69 and raises the weight W. On return to neutral the knob 77 forces the bell-crank to neutral position, thereby positively opening the motor switch. Forward or discharge movement of 40 the operating handles from neutral position causes the arcuate portion 77 of this fifth device to rise and said portion therefore does not cause movement of the bell-crank 45 and therefore does not close the motor switch. The knob 77 at this time engages the upstanding end of the slotted arm 79 of the bell-crank lever and ensures the positive opening of the motor circuit and prevents failure of the interlock system through momentum of sudden reversals of the operating handle OH thus canceling the restoring 50 effort of the weight.

55 The lock handle LH (Figs. 3 and 38 to 41) is located at the rear of the machine, to the left of the middle. The lock handle is pivoted to the lock shaft LS (Figs. 17, 23, 36 and 37) as at 91 (Fig. 38) for movement toward and away from the frame of the machine, so that the free end of the lock handle can be swung toward and away from

the lock L (Fig. 38) mounted on the rear of the machine. The lock handle has a curved portion 93 (Fig. 41) that forms, when the free end of the handle is in locking position, a space for the reception and retention of the hose D and nozzle. As this space has a recess for the reception and retention of collars 94 on the hose coupling between hose and nozzle, neither the hose nor the nozzle can be removed when the lock handle is in locked position. The nozzle 92 has a hook 96 (Figs. 38-41) supported in an ear 98 on the frame. The end of the nozzle extends into a shield or cap 100 protecting the nozzle from rain, dust and the like.

70 The lock L (Figs. 38-41) is preferably a commercial slidable-barrel tumbler-type lock mounted vertically in a bracket 95 (Figs. 38-41) on the rear of the machine at about 75 the top of the third level. The lock bolt 97 has a portion (Fig. 41) approximately semicircular in cross-section, and moves upwardly into locking position. When the machine is to be locked, the lock handle LH 80 is rotated clockwise (Figs. 3 and 38-40) about a quarter-turn to bring the lock handle from its vertical downward or neutral position shown in Fig. 38 to its horizontal leftward (viewed from the rear as in Figs. 85 3 and 38-40) locking position shown in Figs. 39 and 40. The lock handle, which as above described is pivoted on the lock shaft, is then rotated toward the casing, from its Figs. 39 and 41 position to its Fig. 40 position, into the space 99 between the lock barrel housing 95 and the lug 101 above said housing. The lock bolt is then raised into locking position (Fig. 40), thereby preventing the lock handle from being swung outwardly on its shaft, the bracket 95 preventing the lock handle (with its shaft) from being rotated downwardly toward neutral position. The hose D is at this time held 90 between the frame of the machine and the curved portion 93 of the lock handle.

95 The lock shaft LS (Figs. 22-28 and 36-41) has fixed on it four devices L1, L2, L3 and L4.

100 Reading from front to rear of the machine, the first device L1 (Figs. 24-28) is the vertical transverse disc referred to above in connection with the first device O1 on the operating shaft OS. This disc has the slot or notch 57 in it, registering with the operating shaft disc O1, and forming part of the above described interlock between the two shafts preventing either shaft from being moved away from neutral position except when the other shaft is in neutral position.

105 Reading still from front to rear, the second device L2 (Figs. 22, 23, 36 and 37) on the lock shaft comprises a pinion 105 on the lock shaft, engaging a rack 107 that extends upwardly toward the right of the ma- 110

chine, to operate the emptying valve EV. This emptying or draining valve connects the container C to the overflow pipe 33, and is opened by the movement of the lock shaft 5 into locking position. The valve begins to open after the third device L3, described below, has operated to disconnect the totalizer T (Figs. 33-37) from the float F (Figs. 29-32, 36 and 37).

10 The third device L3 (Figs. 24-28, 36 and 37) on the lock shaft LS comprises a spiral cam 109 on the lock shaft, cooperating with the vertical rod 111 (Figs. 36 and 37) that extends upwardly from the third level 15 through the fourth level to the fifth level, where it is pivotally connected to the approximately horizontal arm 112 of a bell-crank lever 113 (Figs. 33 and 34), the vertical arm 114 of which engages a link 120 carrying a gear 115. This gear 115 meshes (when the rod 111 is down) with a gear 117 of the totalizer gearing TG hereinafter described. The gear 115 is part of the float gearing FG, hereinafter described. When 20 the lock shaft is in neutral position (Fig. 36) the rod 111 is down, and the gear 115 is in mesh with the gear 117. Movement of the lock shaft clockwise (viewed from the rear as in Figs. 36 and 37) causes the spiral cam 109 to raise the rod 111, thereby rocking the bell-crank lever 113 and the gear 115 to swing the latter out of engagement with the gear 117. The gears 115 and 117 thus constitute the driving and driven members 25 respectively of a clutch between the float gearing FG and the totalizer gearing TG; and the movement of the lock shaft into locking position opens this clutch, thereby disconnecting the totalizer from the float. As noted above, this disconnection is timed to occur before the emptying 30 valve EV begins to open.

The fourth device L4 (Figs. 38-41) on the lock shaft LS comprises the pivotally mounted lock handle LH which cooperates with the lock L as above described, to serve the dual purpose of locking the hose and nozzle against displacement and of being itself locked against displacement, by the 35 lock L.

The discharge pipe and hose D (Figs. 1, 5 and 38-41) are mounted to receive gasoline from the container through the discharge valve DV associated with the fourth 40 device O4 on the operating shaft, above described. As noted above in connection with the lock L, the hose nozzle end is adapted to fit into a cap 100 (Figs. 38-40) on the rear side of the frame of the machine at 45 about the lower part of the fourth level, and the hose adjacent said nozzle is adapted to be locked into position against said frame by the device L4. There is a cored communication 102 (Fig. 30) between the hose 50 side of the discharge valve and the pipe 104

at the left front side of the fourth level (Fig. 30); this pipe extends up to the fifth level and is there open (Fig. 29), to provide a siphon-breaker for the hose.

70

Fourth level—(Figs. 30-32, 36 and 37).

The container C (Figs. 30-32, 36 and 37) is a vertical glass cylinder having scale legends 119 (Figs. 1 and 3) painted or otherwise marked on it. The scale graduations, however, corresponding to these legends, are not on the glass but are on each of two quantity scales or indicators Q mounted respectively at front and rear just inside the glass, and adjacent the scale legends 119.

75

The quantity scales Q each comprises two rods 121, 123, the former having notches at convenient distances such as $\frac{1}{8}$ inch, and the other being threaded. The notched rod 121 assists the inspector in locating the gallon and fractional-gallon quantity stops 125, 127. On the threaded rod 123 are slidably mounted said stops or plates 125, 127 of appropriate shape, and each plate is held in position by lock nuts 129 above and below it and is located adjacent the glass, to facilitate viewing the plate; the plates are, however, out of contact with the glass, and sufficiently far from it so that during descent of the liquid past the plate the liquid film will break all around the plate. Each plate has a small hole 131 through it. When the liquid is at or above the level of the respective plate, a film of the liquid closes this hole. When the liquid drops below the level of the plate, the film or meniscus breaks at the hole, and also around the outer edge of the plate, and the breaking of the film at the hole and/or about the edges of the plate causes a definite indication of the instant when the liquid passes a predetermined point with respect to the plate or stop.

80

Extending vertically inside the container are the inlet pipe I at the right side, and the overflow pipe 33 at the left side of the middle. The level of the top of the overflow pipe is adjustable by rotating the pipe section 132 (Fig. 32), sealed by gland construction and threaded into the pipe 33.

85

The inlet pipe I terminates at a point 115 adjacent the top of the container C, and on the upper end of the pipe is mounted a spreader or distributor head or supply head 135 (Figs. 30-32) of crescent shape in plan, (Fig. 30), to direct gasoline in a spiral or helical direction against the inside of the glass container and to spread the gasoline around as much of the surface of the glass as may be. This scours the inside surface of the glass at each inlet event, thereby preventing clouding of glass due to accumulated dirt deposits and at the same time reducing objectionable agitation to a minimum, and presents a striking appearance during inlet.

90

95

100

105

110

115

120

125

130

The float F (Figs. 30-32) is preferably of tinned copper and is of generally rectangular shape. A central fixed rod 136 in the container, and two wires 137 on the 5 float and extending adjacent either side of the inlet pipe I serve as guides for the float in its up-and-down movement within the container, and serve to keep it out of contact with the quantity indicators Q and with 10 the wall of the container. Mounted on the float is a chain 139 forming part of the float gearing FG hereinafter described, and mentioned above in connection with the device L3 on the lock shaft. The float when 15 in lowermost position rests upon a support 141 (Figs. 31 and 32), adjustably positioned to limit the downward movement of the float. A similar device 142 (Figs. 31-32) adjustably limits the upward travel of the 20 float.

The protective screen 143 (Figs. 1-5, 30-32 and 36-37) is outside the container C, and is formed in two parts hinged at the left front side of the machine as indicated 25 in Figs. 1, 2 and 30. The free ends of the two parts of the screen thus come together at the right rear of the machine, as shown in Figs. 3, 4 and 30, and are held together by channels 145, held in position by screws 30 147. By swinging open the two parts of the screen the outside of the container may be readily cleaned.

Fifth level—(Figs. 29 and 33-37).

35 The dome 149 (Figs. 1 to 4 and 29) is hinged on the frame at the front of the top of the fourth level. In the rear side of the dome is a glass plate 151 (Fig. 3) to permit reading of the totalizer. A lock or 40 seal 152 (Fig. 29) at either side of the machine prevents opening of the dome and thus prevents tampering with the quantity stops, totalizer and other parts therein.

The totalizer T (Figs. 29 and 33-37) is 45 preferably of the so-called constant-torque-type, and is shown somewhat conventionally as comprising five denominational discs and pointers (Fig. 33) interconnected by suitable gearing and adapted to be driven 50 from the float F through the float gearing FG and totalizer gearing TG hereinafter described.

The totalizer gearing TG (Figs. 29 and 55 33-37) comprises a pinion 153 meshing with the driving gear of the totalizer, and meshing with the gear 117 described above in connection with the totalizer-disconnecting device L3 on the lock shaft.

The float gearing FG (Figs. 33-37) comprises the chain 139 described above in connection with the float F; a drum 165 around which the chain passes; a sleeve 166 on which the drum is mounted; a counter-weight drum 169 having a segment 170 meshing with a pinion 170^a on the sleeve 60

166; a chain 171 around the latter drum; a counterweight 173 fastened to the latter chain; and parts rotated by the drum 165. These parts comprise an internal gear 174 fixed to the drum 165; gears 175, 176 fixed to one another or integral, one on either side of the plate 177, the gears 176 meshing with the internal gear 174, and the gear 175 driving a pinion 179 on a sleeve 181 mounting a pawl-bearer 183 carrying two 65 pawls 185. During inlet the pawls ride idly over the ratchet 187; during discharge they drive the ratchet. Mounted integrally with the ratchet 187 is a second ratchet 189 engaged by pawls 191 to prevent retrograde movement of the ratchets. The ratchets are fixed upon or integral with a sleeve 193 carrying a pinion 195 meshing with the gear 115 described above in connection with the totalizer-disconnecting device L3 on the 70 lock shaft. The link 120 is mounted free to turn in a support frame which in turn carries the fixed shaft 197 that carries the several sleeves above mentioned. During inlet the float rises; the driving pawls 185 of 75 the overrunning clutch at this time ride idly over the teeth of the ratchet 187 associated therewith, and the locking pawls 191 engage the teeth of their ratchet 189 to prevent reverse rotation of the ratchets. During discharge the float descends, and the driving pawls 185 drive their ratchet 187 in a counter-clockwise direction (Fig. 80 33), thereby driving the sleeve 193 in the same direction, and rotating the gears 195 and 115.

As the lock shaft is in neutral position during discharge, the gear 115 is in mesh with the gear 117 of the totalizer gearing, so that the descent of the float operates the 85 totalizer. During emptying, that is, when the operating shaft is in neutral and the lock shaft in locking position, the third device L3 on the lock shaft disengages the gear 115 from the gear 117 of the totalizer 90 gearing, so that descent of the float during emptying does not operate the totalizer.

Sixth level.

Surmounting the dome is a translucent 110 globe 195 (Figs. 1 to 5) containing an electric light for illuminating and/or advertising purposes.

Operation—locked or night position—(Figs. 37 and 40).

The lock L at the rear of the machine at the top of the third level is locked, that is, its bolt 97 is up, and the lock handle LH is thereby locked in horizontal position against the frame of the machine. By the interaction of the lock shaft and the operating shaft through the cooperating notched discs O1, L1, thereon, the operating shaft is thus locked in neutral position, with 120

both handles OH vertical. The by-pass valve BV is locked closed. The weight W is down. The discharge valve DV is locked closed. The motor switch MS is 5 locked open. The emptying valve EV is locked open. The container C is therefore empty. The totalizer is disconnected from the float. If the operator should manage to operate the pump, the gasoline pumped 10 thereby would simply pass into the container and out through the emptying valve EV to the overflow pipe 33, without registering anything on the totalizer.

15 *Unlocking*—(Fig. 39).

By inserting a proper key 196 (Figs. 38-40) in the lock cylinder 197 (Fig. 41) the bolt 97 may be lowered. This permits the lock handle LH to be swung outwardly 20 from its Fig. 40 position to its Fig. 39 position. Then the hose D can be removed. The lock handle can then be turned counterclockwise (viewed from the rear as in Figs. 38-40) from its Fig. 39 position to its Fig. 25 38 position, at which time the handle projects downwardly (neutral position). This brings the notch in the lock shaft disc L1 in registry with the plane of the operating shaft disc O1, so that the operating handles 30 OH are unlocked. This movement of the lock shaft also closes the emptying valve EV and connects the totalizer to the float.

35 *Inlet event*—(Figs. 15, 20 and 27).

When the container C is to have gasoline pumped into it, the operator pulls either 40 operating handle OH toward the rear. The first device O1 thereupon locks the lock shaft LS in neutral position, thereby locking the emptying valve EV closed and connecting the float gearing with the totalizer 45 gearing at the gears 115-117. The second device O2 has no function. The third device O3 raises its vertical link 59 away from the weight lever arm 65 and thus has no function. The fourth device O4 has no function. The fifth device O5 rotates the bell-crank lever 81 clockwise (viewed from the left as in Fig. 19) thereby lowering the 50 horizontal disc 85 and its vertical rod 87, thus raising the weight W and closing the motor switch MS. This starts the motor driving the pump, which pumps gasoline up into the container.

55 When the operator lets go of the operating handle OH, the pump stops, because the weight acts through the bell-crank lever 81 to restore the operating handle to neutral and to open the motor switch MS.

60 If the operator does not release the operating handle before the container gets full, any excess gasoline over five gallons in the container flows out through the overflow pipe in the container.

65 During inlet the float rises, but the over-

running clutch in the float gearing FG allows the totalizer to remain at rest.

70 *Discharge or dispensing event*—(Figs. 16, 21 and 28).

To discharge gasoline from the container, the operator first places the hose nozzle end in the receptacle (not shown) that is to receive the gasoline. He then pulls either 75 operating handle OH forward from neutral position. The first device O1 thereupon locks the lock shaft LS in neutral position, thereby locking the emptying valve DV closed and locking the float in driving connection with the totalizer. The second device O2 opens the by-pass valve BV from inlet to overflow, thereby preventing the passage of any further gasoline from pump to 80 container, even if the operator pumps by means of the hand crank HC. The third device O3 acts through the vertical link 59 to raise the weight W. The fourth device O4 opens the discharge valve DV. The fifth device O5 holds the bell-crank lever 81 in proper position for keeping the motor switch MS open.

The operator can stop the discharge event at any instant by releasing pressure on the operating handle OH. He does so when the gasoline has dropped to the desired level. This level is ascertained by looking at the quantity legends 119 and the adjacent quantity stops 125, 127.

When pressure on the operating handle is released, the weight W causes the handle to return to neutral, and no further discharge takes place. The operator and customer are thus able to read at leisure the amount of gasoline that has been discharged from the container.

During discharge the float descends, and through the float gearing FG and totalizer gearing TG the totalizer is operated to register the quantity of gasoline discharged.

110 *Emptying or draining event*—(Figs. 38-41).

To empty or drain the container back to the reservoir, the operator simply shifts the lock handle LH to locking position (Figs. 39 and 40), thereby first disconnecting the totalizer from the float through the device L3, and thereafter opening the emptying valve EV through the device L2.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. In a dispensing device having a container with means to admit liquid to the container and to discharge liquid from the container, and a totalizer, a lock shaft operatively connected with said means and totalizer, and a lock handle operable to actuate the lock shaft to locking position to disconnect the totalizer.
2. A dispensing device having a container with means to admit liquid to the container and to discharge liquid from the container, and a totalizer for registering the amount of liquid discharged from the container, a lock shaft operatively connected with said means, and a lock handle operable to actuate the lock shaft to locking position to prevent inlet to the container or discharge from the container.
3. A dispensing device having a container with means to admit liquid to the container and to discharge liquid from the container and to empty the container, and a totalizer for registering the amount of liquid discharged from the container, a lock shaft operatively connected with said means and totalizer, and a lock handle operable to actuate the lock shaft into locking position to disconnect the totalizer and empty the container.
4. An apparatus of the class described, in combination, a container, means to admit liquid to the container and to discharge liquid from the container, said means including an operating shaft, a lock shaft, an interlock between said shafts for locking said operating shaft against movement, a totalizer for registering the amount of liquid discharged, and a connection between said totalizer and said lock shaft whereby said totalizer is disconnected when said lock shaft is moved to a position to lock said operating shaft.
5. An apparatus of the class described, in combination, a totalizer, means including an operating shaft to admit liquid to the container and to discharge liquid from the container, a lock shaft, an interlock between said shafts for locking said operating shaft against movement, and a connection between said container and said lock shaft whereby inlet to the container or discharge from the container is prevented when said lock shaft is moved to a position to lock said operating shaft.
6. An apparatus of the class described, in combination, a container, a totalizer, an emptying device for emptying the container, means to admit liquid to the container and to discharge liquid from the container, said means including an operating shaft, a lock shaft, an interlock between said shafts for locking said operating shaft against movement, and connections between said lock shaft, emptying device, and totalizer, where-
by said totalizer is disconnected and said container is emptied when said lock shaft is moved to a position to lock said operating shaft.
7. An apparatus of the class described, in combination, a container, an emptying device for emptying the container, means to admit liquid to the container and to discharge liquid from the container to a discharge hose, said means including an inlet and discharge operating shaft, a lock shaft, an interlock between said shafts, a connection between the lock shaft and emptying device, means operable by said lock shaft to lock the hose in inoperative position, and a lock handle operable to actuate said lock shaft, and to lock said operating shaft whereby said container is emptied and said hose is secured against operation.
8. An apparatus of the class described, in combination, means to admit liquid to the container and to discharge liquid from the container to a discharge hose, said means including an inlet and discharge operating shaft, and a lock handle operable to secure said hose against operation and to actuate said lock shaft and to lock said operating shaft in locking position whereby inlet to the container or discharge from the container is prevented.
9. An apparatus of the class described, in combination, a container, a totalizer adapted to register the liquid discharged from the container, means to admit liquid to the container and to discharge liquid from the container to a discharge hose, said means including an inlet and discharge operating shaft, a lock shaft, means operable by said lock shaft to lock said hose in inoperative position, an interlock between said shafts, a connection between said totalizer and said lock shaft, and a lock handle operable to actuate the lock shaft into locking position whereby operation of said totalizer is prevented and said hose is secured against operation, said operating shaft being locked by said lock shaft when said hose is secured against operation to prevent movement of said inlet or discharge means to inlet or discharge positions.
10. An apparatus of the class described, in combination, a container, and means for admitting liquid thereto, said means comprising a distributor head adjacent the upper end of the container for discharging the liquid spirally or helically upon the inner surface of the container whereby the inner surface of the container is scoured at each inlet.
11. An apparatus of the class described, in combination, a container, a totalizer, a float in the container, a clutch having driving and driven members, gearing connecting the float to the driving member during movement of the float in one direction and dis-

connecting the float from the driving member during reverse movement of the float, gearing connecting the driven member to the totalizer, and means inoperative during 5 inlet and discharge to open the clutch said means controllable from a manually operable exterior member.

12. In apparatus of the class described, in combination, a container, an inlet device for 10 admitting liquid thereto, a discharge device for discharging liquid therefrom, an emptying device for emptying the container, a totalizer, a float in the container, a clutch having driving and driven members, gearing connecting the float to the driving member during movement of the float in one direction and disconnecting the float from the driving member during reverse movement of the float, gearing connecting the 15 driven member to the totalizer, and means inoperative during inlet and discharge to open the clutch said means including a lock shaft having an intermediate connection with said clutch.

13. In apparatus of the class described, in combination, a container, a totalizer, a device responsive to the amount of liquid passing to or from the container, gearing connecting said last-named device to the totalizer to drive the totalizer, a clutch in said 20 gearing, means for locking the apparatus, said locking means being inoperative during inlet and discharge, and means opening the clutch automatically by the movement of 25 said locking means in locking direction.

14. In apparatus of the class described, in combination, a container, an inlet device for admitting liquid thereto, a discharge device for discharging liquid therefrom, an emptying device for emptying the container, a totalizer, a device responsive to the amount 30 of liquid passing to or from the container, gearing connecting said last-named device to the totalizer to drive the totalizer in one 35 direction only, a clutch in said gearing, means operable into locking position to disconnect the totalizer and means dependent on said first mentioned means and inoperative during inlet and discharge to open the 40 clutch.

15. In apparatus of the class described, in combination, a container, a totalizer, a float in the container, a clutch having driving and driven members, gearing connecting the 45 float to the driving member, gearing connecting the driven member to the totalizer, and means for locking the apparatus, said locking means including a lock shaft, and a lock handle adapted to actuate said lock 50 shaft into locking position whereby said locking means is inoperative during inlet and discharge, said first means being operative to open the clutch automatically when said locking means is actuated to locking 55 position.

16. In apparatus of the class described, in combination, a container, an inlet device for admitting liquid thereto, a discharge device for discharging liquid therefrom to a hose, means for locking the hose in inoperative 60 position, and an interlock between the hose-locking means and the inlet and discharge devices, whereby said locking means is operative when the inlet and discharge devices 65 are inoperative.

17. In apparatus of the class described, in combination, a container, an inlet device for admitting liquid thereto, a discharge device for discharging liquid therefrom to a hose, means for locking the hose in inoperative 70 position, and an interlock between the hose-locking means and the inlet and discharge devices, whereby said locking means is operative when the inlet and discharge devices 75 are inoperative.

18. In apparatus of the class described, in combination, a container, an inlet device for admitting liquid thereto, a discharge device for discharging liquid therefrom to a hose, a totalizer, means operating the totalizer 80 during flow of liquid from the container, means for locking the hose in inoperative position, and an interlock between the hose-locking means and the inlet and discharge devices, whereby said locking means is operative 85 when the inlet and discharge devices are inoperative.

19. An apparatus of the class described, in combination, a container, having a discharge device, an emptying device for 90 emptying the container, a totalizer, means operating the totalizer during the discharge of liquid from the container, connections between the totalizer operating means and the emptying device for disconnecting the 95 totalizer during the emptying of said container, and an interlock between the emptying and discharge devices to open the emptying device when said discharge device is closed.

20. An apparatus of the class described, in combination, a container, an inlet device for admitting liquid thereto, a discharge device comprising a hose for discharging liquid therefrom, an emptying device for 100 emptying the container, a totalizer, means operating the totalizer only during the discharge of liquid from the container, a connection between said totalizer and said emptying and inlet devices whereby said 105 totalizer is disconnected during flow of liquid to the container and during emptying of the container, connections between the inlet and discharge devices and the emptying device for disconnecting the inlet and discharge devices when the emptying device is open, means for locking the discharge hose in inoperative position and an interlock between the hose locking means and the emptying means whereby the lock- 110

115

130

from neutral position, the inlet device comprising a motor and a pump, actuated thereby for supplying liquid to the container, a switch for controlling the motor, and connections between said operating shaft and said switch the movement of the operating shaft to open the discharge device positively preventing energization of the motor.

31. In apparatus of the class described, in combination, a container, a hose and nozzle, an inlet device for admitting liquid to the container, a discharge device for discharging liquid therefrom to the hose and nozzle, a totalizer, an operating shaft actuating the inlet and discharge devices by movement of the shaft in opposite directions from neutral position, the inlet device comprising a motor and a pump, actuated thereby for supplying liquid to the container, a switch for controlling the motor, and connections between said operating shaft and said switch, the movement of the operating shaft to open the discharge device positively preventing energization of the motor, and interlocking means on the two shafts preventing movement of either shaft save when the other shaft is in neutral position.

32. In apparatus of the class described, in combination, a container, an overflow conduit extending through said container, a hose and nozzle, an inlet device for admitting liquid to the container, a discharge device for discharging liquid therefrom to the hose and nozzle, a by-pass from said overflow conduit to said inlet, a totalizer, a lock, a lock handle adapted to be secured in locking position by the lock and adapted to secure in inoperative position the hose and nozzle, a lock shaft operated by the lock handle, means for operating the totalizer during discharge of liquid from the container, an operating shaft actuating the inlet and discharge devices by movement of the shaft in opposite directions from neutral position, the inlet device comprising a motor and a pump, the movement of the operating shaft to discharge position positively preventing energization of the motor and opening the by-pass from inlet conduit to overflow conduit, interlocking means on the two shafts preventing movement of either shaft save when the other shaft is in neutral position, and a weight lifted by movement of the operating shaft in either direction from neutral and tending to restore said shaft to neutral position.

33. In apparatus of the class described, in combination, a container, a hose and nozzle, an inlet device for admitting liquid to the container, a discharge device for discharging liquid therefrom to the hose and nozzle, an emptying device for emptying the container, a totalizer, a lock, a lock handle adapted to be secured in locking position by the lock and adapted to secure in inopera-

tive position the hose and nozzle, a lock shaft operated by the lock handle, means for operating the emptying device by movement of the lock shaft, and means for disconnecting the totalizer by said movement but prior to the operation of the emptying device.

34. In apparatus of the class described, in combination, a container, a hose and nozzle, an inlet device for admitting liquid to the container, a discharge device for discharging liquid therefrom to the hose and nozzle, an emptying device for emptying the container, a totalizer, a lock, a lock handle adapted to be secured in locking position by the lock and adapted to secure in inoperative position the hose and nozzle, a lock shaft operated by the lock handle, and means for operating the emptying device by movement of the lock shaft to locking position.

35. In apparatus of the class described, in combination, a container, an overflow conduit extending through said container, a hose and nozzle, an inlet device for admitting liquid to the container, a discharge device for discharging liquid therefrom to the hose and nozzle, a by-pass from said overflow conduit to said inlet, an emptying device for emptying the container, a totalizer, a lock, a lock handle adapted to be secured in locking position by the lock and adapted to secure in inoperative position the hose and nozzle, a lock shaft operated by the lock handle, means for operating the totalizer during discharge of liquid from the container, means for operating the emptying device by movement of the lock shaft to locking position, means for disconnecting the totalizer by said movement but prior to the operation of the emptying device, an operating shaft actuating the inlet and discharge devices by movement of the shaft in opposite directions from neutral position, the inlet device comprising a motor and a pump actuated thereby for supplying liquid to the container, a switch for controlling the motor, and connections between said operating shaft and said switch, the movement of the operating shaft to open the discharge device positively preventing energization of the motor and opening the by-pass from inlet conduit to overflow conduit, interlocking means on the two shafts preventing movement of either shaft save when the other shaft is in neutral position, and a weight lifted by movement of the operating shaft in either direction from neutral and tending to restore said shaft to neutral position.

36. In apparatus of the class described, in combination, a container, an overflow conduit extending through said container, an inlet device for admitting liquid thereto, a discharge device for discharging liquid therefrom, a by-pass from said overflow conduit to said inlet, a totalizer, a lock, a

- lock handle adapted to be secured in locking position by the lock, a lock shaft operated by the lock handle, means for operating the totalizer during discharge of liquid from the container, an operating shaft actuating the inlet and discharge devices by movement of the shaft in opposite directions from neutral position, the inlet device comprising a motor and a pump actuated thereby for supplying liquid to the container, a switch for controlling the motor, and connections between said operating shaft and said switch, the movement of the operating shaft to open the discharge device positively preventing energization of the motor.
41. In apparatus of the class described, in combination, a container, an overflow conduit extending through said container, a hose, an inlet device for admitting liquid to the container, a discharge device for discharging liquid therefrom to a hose, a by-pass from said overflow conduit to said inlet, a pair of operating handles, an operating shaft connected thereto and actuating the inlet and discharge devices by movement of the shaft in opposite directions from neutral position, the inlet device comprising a motor and a pump actuated thereby for supplying liquid to the container, a switch for controlling the motor, and connections between said operating shaft and said switch, the movement of the operating shaft to open the discharge device positively preventing energization of the motor and opening the by-pass from inlet conduit to overflow conduit.
42. In apparatus of the class described, in combination, a container, an overflow conduit extending through said container, a hose, an inlet device for admitting liquid to the container, a discharge device for discharging liquid therefrom to a hose, a by-pass from said overflow conduit to said inlet, a pair of operating handles, an operating shaft connected thereto and actuating the inlet and discharge devices by movement of the shaft in opposite directions from neutral position, the inlet device comprising a motor and a pump actuated thereby for supplying liquid to the container, a switch for controlling the motor, and connections between said operating shaft and said switch, the movement of the operating shaft to open the discharge device positively preventing energization of the motor and opening the by-pass from inlet conduit to overflow conduit.
43. In apparatus of the class described, in combination, a container, a hose, an inlet device for admitting liquid to the container, a discharge device for discharging liquid therefrom to a hose, a pair of operating handles, an operating shaft connected thereto and actuating the inlet and discharge devices by movement of the shaft in opposite directions from neutral position, and a weight lifted by movement of the operating shaft in either direction from neutral and tending to restore said shaft to neutral position.
44. In apparatus of the class described, in combination, a container, a hose, an inlet device for admitting liquid to the container, a discharge device for discharging liquid therefrom to a hose, a pair of operating handles, and an operating shaft connected thereto and actuating the inlet and discharge devices by movement of the shaft in opposite directions from neutral position, the inlet device comprising a motor and a pump actuated thereby for supplying liquid to the container, a switch for controlling the motor, and connections between said operating shaft and said switch, the movement of the operating shaft to open the discharge device positively preventing energization of the motor and opening the by-pass from inlet conduit to overflow conduit, and a weight lifted by movement of the operating shaft in either direction from neutral and tending to restore said shaft to neutral position.
45. In apparatus of the class described, in combination, a container, a hose, an inlet device for admitting liquid to the container, a discharge device for discharging liquid therefrom to a hose, a pair of operating handles, and an operating shaft connected thereto and actuating the inlet and discharge devices by movement of the shaft in opposite directions from neutral position, the inlet device comprising a motor and a pump actuated thereby for supplying liquid to the container, a switch for controlling the motor, and connections between said operating shaft and said switch, the movement of the operating shaft to open the discharge device positively preventing energization of the motor and opening the by-pass from inlet conduit to overflow conduit, and a weight lifted by movement of the operating shaft in either direction from neutral and tending to restore said shaft to neutral position.
46. In apparatus of the class described, in combination, a container, a hose, an inlet device for admitting liquid to the container, a discharge device for discharging liquid therefrom to a hose, an emptying device for emptying the container, a totalizer, a lock, a lock handle adapted to be secured in locking position by the lock and adapted to secure the hose in inoperative position, and a lock shaft operated by the lock handle, means for operating the totalizer during discharge of liquid from the container, means

for operating the emptying device by movement of the lock shaft to locking position, and means for disconnecting the totalizer by said movement but prior to the operation 5 of the emptying device.

44. In apparatus of the class described, in combination, a container, an overflow conduit extending through said container, a hose, an inlet device for admitting liquid 10 to the container, a discharge device for discharging liquid therefrom to a hose, a by-pass from said overflow conduit to said inlet, an emptying device for emptying the container, a totalizer, a lock, a lock handle 15 adapted to be secured in locking position by the lock and adapted to secure the hose in inoperative position, a lock shaft operated by the lock handle, means for operating the totalizer during discharge of liquid from the 20 container, means for operating the emptying device by movement of the lock shaft to locking position, means for disconnecting the totalizer by said movement but prior to the operation of the emptying device, a pair 25 of operating handles, an operating shaft connected thereto and actuating the inlet and discharge devices by movement of the shaft in opposite directions from neutral position; the inlet device comprising a motor 30 and a pump actuated thereby for supplying liquid to the container, a switch for controlling the motor, and connections between said operating shaft and said switch, the movement of the operating shaft to open 35 the discharge device positively preventing energization of the motor and opening the bypass from inlet conduit to overflow conduit, interlocking means on the two shafts preventing movement of either shaft save when 40 the other shaft is in neutral position, and a weight lifted by movement of the operating shaft in either direction from neutral and tending to restore said shaft to neutral position.

45. In apparatus of the class described, in combination, a container, an inlet device for admitting liquid to the container, a discharge device for discharging liquid therefrom, an operating handle, an operating 50 shaft connected thereto and actuating the inlet and discharge devices by movement of the shaft in opposite directions from neutral position, and a weight lifted by movement of the operating shaft in either direction from neutral 55 position, the shaft connected thereto and actuating the inlet and discharge devices by movement of the shaft in opposite directions from neutral position, and a weight lifted by movement of the operating shaft in either direction from neutral position.

46. In apparatus of the class described, in combination, a container, an inlet device for admitting liquid to the container, a discharge device for discharging liquid therefrom, an operating handle, and an operating shaft connected thereto and actuating the inlet and discharge devices by movement of the shaft in opposite directions from neutral 60 position, the inlet device comprising a motor 65

and a pump actuated thereby for supplying liquid to the container, a switch for controlling the motor, and connections between said operating shaft and said switch, the movement of the operating shaft to open 70 the discharge device positively preventing energization of the motor.

47. In apparatus of the class described, in combination, a container, an overflow conduit extending through said container, an inlet device for admitting liquid to the container, a discharge device for discharging liquid therefrom, a by-pass from said overflow conduit to said inlet device, an operating handle and an operating shaft connected 80 thereto and actuating the inlet and discharge devices by movement of the shaft in opposite directions from neutral position, the inlet device comprising a motor and a pump actuated thereby for supplying liquid 85 to the container, a switch for controlling the motor, and connections between said operating shaft and said switch, the movement of the operating shaft to open the discharge device positively preventing energization of the motor and opening the bypass from inlet conduit to overflow conduit.

48. In apparatus of the class described, in combination, a container, an inlet device for admitting liquid to the container, a discharge device for discharging liquid therefrom, a lock, a lock handle adapted to be secured in locking position by the lock, a lock shaft operated by the lock handle, an operating handle, an operating shaft connected 95 thereto and actuating the inlet and discharge devices by movement of the shaft in opposite directions from neutral position, and interlocking means on the two shafts preventing movement of either shaft save when 100 the other shaft is in neutral position.

49. In apparatus of the class described, in combination, a container, an inlet device for admitting liquid to the container, a discharge device for discharging liquid therefrom, a lock, a lock handle adapted to be secured in locking position by the lock, a lock shaft operated by the lock handle, an operating handle, an operating shaft connected thereto and actuating the inlet and 110 discharge devices by movement of the shaft in opposite directions from neutral position, interlocking means on the two shafts preventing movement of either shaft save when the other shaft is in neutral position, and a weight lifted by movement of the operating shaft in either direction from neutral and tending to restore said shaft to neutral position.

50. In apparatus of the class described, in combination, a container, an inlet device for admitting liquid to the container, a discharge device for discharging liquid therefrom, an emptying device for emptying the container, a lock, a lock handle adapted to 125

be secured in locking position by the lock, a lock shaft operated by the lock handle, and means for operating the emptying device by movement of the lock shaft to locking position.

51. In apparatus of the class described, in combination, a container, an inlet device for admitting liquid to the container, a discharge device for discharging liquid therefrom, an emptying device for emptying the container, a lock, a lock handle adapted to be secured in locking position by the lock, a lock shaft operated by the lock handle, means for operating the emptying device by movement of the lock shaft to locking position, and an operating handle, an operating shaft connected thereto and actuating the inlet and discharge devices by movement of the shaft in opposite directions from neutral position.

52. In apparatus of the class described, in combination, a container, an overflow conduit extending through said container, a hose and nozzle adapted to receive liquid discharged from the container, an inlet device for admitting liquid to the container, a discharge device for discharging liquid therefrom, an emptying device for emptying the container, a by-pass from said overflow conduit to said inlet device, a lock, a lock handle adapted to be secured in locking position by the lock and adapted to secure in inoperative position the hose and nozzle, a lock shaft operated by the lock handle, means for operating the emptying device by movement of the lock shaft to locking position, an operating handle, an operating shaft connected thereto and actuating the inlet and discharge devices by movement of the shaft in opposite directions from neutral position, the inlet device comprising a motor and a pump, actuated thereby for supplying liquid to the container, a switch for controlling the motor, and connections between said operating shaft and said switch, the movement of the operating shaft to open the discharge device positively preventing energization of the motor and opening the by-pass from inlet conduit to overflow conduit, interlocking means on the two shafts preventing movement of either shaft save when the other shaft is in neutral position, and a weight lifted by movement of the operating shaft in either direction from neutral and tending to restore said shaft to neutral position.

53. In apparatus of the class described, in combination, a container, a discharge conduit, a dome above the container, a pipe supporting the dome and open at the top, and a conduit between said first conduit and said pipe and operating as a siphon-breaker for said first conduit.

54. In apparatus of the class described, in combination, a container, a discharge conduit, a dome above the container, a pipe

supporting the dome and open at the top within the dome, and a conduit between said first conduit and said pipe and operating as a siphon-breaker for said first conduit.

55. In apparatus of the class described, in combination, a translucent container, means for admitting liquid thereto and for discharging liquid therefrom, quantity legends and a quantity indicator within the container and comprising stops, one or more of said stops having apertures therein bridged by liquid when the liquid level is at or above the stop.

56. In apparatus of the class described, in combination, a translucent container, means for admitting liquid thereto and for discharging liquid therefrom, quantity legends and a quantity indicator within the container and comprising a threaded shaft having quantity stops on it each secured in position, one or more of said stops having apertures therein bridged by liquid when the liquid level is at or above the stop.

57. In apparatus of the class described, in combination, a translucent container, means for admitting liquid thereto and for discharging liquid therefrom, quantity legends, a quantity indicator within the container and comprising a threaded shaft having quantity stops on it each secured in position, one or more of said stops having apertures therein bridged by liquid when the liquid level is at or above the stop, whereby the breaking of the liquid film across said aperture furnishes a readily visible indication of the moment when the liquid level reaches a predetermined point with respect to the stop.

58. In apparatus of the class described, in combination, a translucent container, means for admitting liquid thereto and for discharging liquid therefrom, quantity legends on the container, a quantity indicator within the container and comprising a threaded shaft having quantity stops on it each secured in position by lock nuts above and below the stop, and a notched shaft facilitating setting of said stops, one or more of said stops having apertures therein bridged by liquid when the liquid level is at or above the stop, whereby the breaking of the liquid film across said aperture furnishes a readily visible indication of the moment when the liquid level reaches a predetermined point with respect to the stop.

59. In apparatus of the class described, in combination, a translucent container, means for admitting liquid thereto and for discharging liquid therefrom, and a quantity indicator within the container and comprising a series of quantity stops each perforated, the breaking of the liquid film across the perforation during descent of the liquid furnishing a readily visible indication of the moment when the liquid

- reaches a predetermined point with respect to the stop.
60. In apparatus of the class described, in combination, a translucent container, means for admitting liquid thereto and for discharging liquid therefrom, quantity indicators within the container for visibly indicating the amount of liquid being discharged from the container, and comprising a shaft having a series of horizontal quantity plates threaded thereon and associated with respective legends on said container, said plates being adjacent the walls of said container and out of contact therewith, the breaking of the liquid film around the plates furnishing a readily visible indication at the moment when the liquid reaches the level of the respective quantity legend.
61. In apparatus of the class described, in combination, a translucent container, means for admitting liquid thereto and for discharging liquid therefrom, and quantity indicators within the container and comprising a series of horizontal quantity plates, the breaking of the liquid film about the plate during descent of the liquid furnishing a readily visible indication of the moment when the liquid reaches a predetermined level with respect to the plate.
62. In apparatus of the class described, in combination, a translucent container, means for admitting liquid thereto and for discharging liquid therefrom, quantity legends on the container, and a quantity indicator within the container and comprising a series of horizontal quantity plates associated with the respective legends, and adjacent the walls of the container but out of contact therewith, the breaking of the liquid film about the plate during the descent of the liquid furnishing a readily visible indication at the moment when the liquid reaches the level of the respective quantity legend.
63. In apparatus of the class described, in combination, a translucent container, means for admitting liquid thereto and for discharging liquid therefrom, quantity indicators within the container for visibly indicating the amount of liquid being discharged from the container, and comprising a shaft having a series of horizontal quantity plates threaded thereon and associated with respective legends on said container, said plates being adjacent the walls of said container and out of contact therewith, the breaking of the liquid film across the aperture and around the plates furnishing a readily visible indication at the moment when the liquid reaches the level of the respective quantity legend.
64. In apparatus of the class described, in combination, a translucent container, means to admit liquid to the container and to discharge liquid from the container, means to register the amount of liquid discharged from the container, and quantity indicators within the container for visibly indicating the amount of liquid being discharged from the container, and comprising a shaft having a series of quantity plates, each perforated, and threaded thereon and associated with respective legends on said container, said plates being adjacent the walls of said container and out of contact therewith, the breaking of the liquid film across the aperture and around the plates furnishing a readily visible indication at the moment when the liquid reaches the level of the respective quantity legend.

In testimony whereof, I have signed my name to this specification this 28th day of June, 1921.

SHERWOOD HINDS.
